US00D781024S

(12) **United States Design Patent** (10) Patent No.: **US D781,024 S**
King et al. (45) Date of Patent: ** Mar. 7, 2017

(54) **MULTISPACE PARKING PAY STATION**

(71) Applicant: **IPS Group Inc.**, San Diego, CA (US)

(72) Inventors: **David William King**, Rancho Santa Fe, CA (US); **Murray David Kirby**, Birchgrove (AU); **David Hunter**, Birchgrove (AU); **David Andrew Jones**, Beecroft (AU); **Choor Hong Tan**, Wentworth Point (AU); **Michael W MacCollum**, Poway, CA (US); **Ron Lawrence**, San Diego, CA (US); **Anthony Babaran**, San Diego, CA (US)

(73) Assignee: **IPS GROUP INC.**, San Diego, CA (US)

(**) Term: **15 Years**

(21) Appl. No.: **29/545,046**

(22) Filed: **Nov. 9, 2015**

CLAIM

The ornamental design for a multispace parking pay station, as shown and described.

DESCRIPTION

FIG. 1 is a top front perspective view of a multispace parking pay station, showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines shown in the drawings represent portions of the multispace parking pay station that form no part of the claimed design.

All surfaces not shown form no part of the claimed design.
